UNITED STATES PATENT OFFICE.

JOHN T. COONEY, OF DENVER, COLORADO.

HAT-FASTENER.

1,218,838.

Specification of Letters Patent. Patented Mar. 13, 1917.

Application filed July 10, 1916. Serial No. 108,392.

To all whom it may concern:

Be it known that I, JOHN T. COONEY, a citizen of the United States, residing at Denver, in the county of Denver and State of Colorado, have invented certain new and useful Improvements in Hat-Fasteners; and I do declare the following to be a full, clear, and exact description of the invention, such as will enable others skilled in the art to 10 which it appertains to make and use the same.

This invention relates to improvements in fasteners for ladies' hats.

The object of the invention is to provide 15 a simply and cheaply constructed device of this character which may be conveniently mounted in a hat and readily changed from one hat to another; and which is so constructed that the sections thereof will be 20 normally held centered and in longitudinal alinement.

With the foregoing and other objects in view, which will appear as the description proceeds, the invention resides in the combination and arrangement of parts and in the 25 details of construction hereinafter described and claimed, it being understood that changes in the precise embodiment of the invention herein disclosed may be made 30 within the scope of what is claimed without departing from the spirit of the invention.

In the accompanying drawings:—

Figure 1 represents a transverse sectional view of a hat showing this improved fastener applied, with the jaws shown closed; 35

Fig. 2 is a similar view with the jaws open;

Fig. 3 is a top plan view of the connected 40 jaw carrying ends of the fastener with the resilient holding member omitted, the jaws shown closed;

Fig. 4 is a detail perspective view thereof with the jaws open;

Fig. 5 is a side elevation showing a 45 slightly different form;

Fig. 6 is a front elevation of the wear plate used in connection with this fastener.

In the embodiment illustrated, H designates the hat to which the improved fastener 50 constituting this invention is shown applied, the opposed side walls of said hat having wear plates 1 and 2 secured on the inner faces thereof at diametrically opposite points, each of said plates being provided 55 with an aperture 3 for the passage therethrough of the stems of the members of the

fastener to be described, so that perforations at various points in the hat will be avoided and the formation of large holes by the continued use of the fastener prevented. 60

This fastener comprises two sections 4 and 5 which are exactly alike and hence the section 5 only will be described in detail. This section 5 comprises a stem or shank 6 composed of any suitable material, 65 preferably of steel wire, and which is pointed at its outer end as shown at 17 to adapt it to penetrate the material of the hat. This stem is also threaded for some distance inwardly from said pointed end to 70 receive a securing head 8 which has an internally threaded neck 9 for detachable engagement with the pointed end of the stem 6. This head 8 may be of any suitable or desired construction and ornamented in any 75 suitable manner to render the device attractive. The inner end of the stem 6 is bent to form a loop 10, the terminal of which is bent to form a laterally extending hook 11.

Engaged with the loop 10 of the stem 6 80 is a prong carrying element 12 composed of a piece of heavy steel wire folded upon itself midway the ends thereof and with its members arranged parallel and adjacent each other preferably in contact to form an arm 85 13, said members being offset inwardly at the inner end of said arm as shown at 14 and then bent forwardly and offset outwardly and forming a loop 15 which is interlockingly engaged with the loop 10 of the stem 90 6, as shown clearly in Figs. 3 and 4, and preferably soldered thereto. The members of the folded wire diverge from the other end of the loop 15 to form parallel prongs 95 16 and 17 which are preferably pointed at their free ends to facilitate their insertion in 100 the hair of the wearer. These prongs 16 and 17 as shown, correspond in length to the arm 13 although they need not necessarily be of the same length.

The free ends of the arms 13 of each section are bent laterally outward to form eyes 18 and 19 through which a connecting and guiding rod 20 is passed, said rod being of substantially the same length as the combined 105 length of the arms 13 of the two sections.

The rod 20 is provided at its opposite ends with eyes 21 and 22 through which an elastic connecting element is designed to pass and which is engaged at its opposite ends 110 with the hooks 11 formed on the stems 6 and positioned at the inner ends of the prong-

carrying elements 12. This elastic element may be either in the form of a cord 23' having a coiled spring at each end (see Fig. 5), or an elastic rubber band or strap 23 shown in Figs. 1 and 2 may be used, as desired. This elastic element taken in connection with the rod 20 serves to hold the sections 4 and 5 centered and in longitudinal alinement to prevent them from wabbling, and holds the laterally extending eyes 21 and 22 of the arms 13 in abutting relation.

By constructing this fastener as above described, and connecting the sections thereof by the rod and elastic element, the necessity of having supports for mounting the sections on the hat crown other than those through which the stems pass, is avoided.

In the use of this fastener, the wear plates 1 and 2 having been secured to the inner face 20 of the opposite sides of the hat crown by any suitable means, the head 9 of one section is removed and the pointed end of the stem thereof is inserted through the aperture in one of the wear plates and projected 25 through the side wall of the hat. This section stem is then moved outwardly to its extreme limit or until the hook 11 at its inner end abuts against the wear plate, and when in this position the pointed end of the stem 30 of the other section may be engaged with the wear plate at the opposite side of the hat crown in a similar manner. When these sections have been so inserted, the heads 9 are replaced on their outer ends and the device 35 is ready for use, the elastic connecting element serving to hold the prongs thereof in closed position, as shown in Fig. 1.

When it is desired to attach the hat to the hair of the wearer, the heads 8 of the sections 40 are grasped and pulled outwardly against the tension of the spring or band which connects the sections, and on the release of said heads the prongs of the sections will move inwardly toward each other and 45 penetrate the hair of the wearer, thereby securely connecting the hat to the wearer's hair.

I claim:—

1. A hat fastener comprising two sections 50 each having a stem provided with a detach-

able head at one end and with longitudinally extending laterally spaced parallel prongs at its other end, an arm also extending longitudinally from said pronged end, said arm being arranged in a plane between the 55 plane of said prongs and spaced laterally therefrom, said arm being of the same length as said prongs, a combined stop and guide eye extending laterally from the free end of each arm and adapted to engage 60 when the sections are at their extreme inward limit, a hook extending laterally from the base of each arm in the same direction as its guide eye, a connecting and guiding rod slidably mounted in the eyes of the two 65 section arms and having eyes at its opposite ends, and an elastic element engaged at its opposite ends with the hooks of the two sections and threaded through the eyes of said rod.

2. A hat fastener comprising two sections each composed of a prong member and a stem, the prong member being formed of a wire bent upon itself intermediate of its ends with the members thereof arranged 75 parallel and adjacent each other to form an arm, said members being offset inwardly at the inner end of said arm and then bent forwardly and offset outwardly and diverged at the outer end of the offset to form parallel prongs, the free end of said arm being bent laterally outward to form a guide eye, a stem for each section having its inner end bent to form a loop for interlocking engagement with the bend at the base of the prong 80 member, said stem being arranged longitudinally relative to said prong member, with the terminal of said loop bent laterally to form a hook, a rod passing through the eyes of the arms of said sections, and an elastic 85 element connecting the hooks of said sections and engaging said rod.

In testimony whereof I have hereunto set my hand in the presence of two subscribing witnesses.

JOHN T. COONEY.
